TOWEL RACK

Mark O. Uitz, Mountain View, Calif., assignor to F. J. L. Corporation, Palo Alto, Calif., a corporation of California

Filed May 8, 1969, Ser. No. 17,071

Term of patent 14 years

Int. Cl. D6—01

U.S. Cl. D33—32

FIG. 1 is a perspective view of a towel rack, showing my new design, one support arm being broken away for convenience of illustration;

FIG. 2 is an elevational view taken from the left end thereof;

FIG. 3 is an elevational view taken from the right end thereof;

FIG. 4 is a front elevational view thereof; and

FIG. 5 is a bottom plan view thereof, one support arm being broken away for convenience of illustration.

The broken line representation of a support bracket in FIGS. 2 and 3 and the fragmentary broken line representation of a wall in FIGS. 2, 3 and 5 are for purposes of illustration only.

I claim:

The ornamental design for a towel rack, as shown and described.
